UNITED STATES PATENT OFFICE.

WILLIAM WALLACE ODELL, OF URBANA, ILLINOIS.

PROCESS OF MANUFACTURING WATER-GAS.

REISSUED

1,379,038.

Specification of Letters Patent. Patented May 24, 1921.

Application filed November 7, 1918. Serial No. 261,567.

To all whom it may concern:

Be it known that I, WILLIAM WALLACE ODELL, a chemical engineer, and a citizen of the United States, residing at Urbana, 5 in the county of Champaign and State of Illinois, have invented new and useful Improvements in Processes of Making Water-Gas.

This invention relates to the manufacture 10 of gas by an intermittent process in which fuel is first heated to a high temperature in a generator by means of an air blast, after which the gas is manufactured, chiefly, by passing steam either up or down through 15 the incandescent fuel, but with improvements in the process consisting in admitting some air with the steam during the steam runs, and under certain specified conditions admitting steam with the air during 20 blasting.

The objects of the invention are, while using any of the aforesaid fuels:

(1) To maintain a more uniform and steady heat in the generator and at the 25 same time a longer gas making period.

(2) To maintain control over the temperatures in carbureter and superheater.

(3) To avoid the waste due to burning 30 gases outside the water gas set by burning them in the carbureter and superheater. (Blast gases.)

(4) To overcome the smoke nuisance by burning all the tarry matter and smoke in the carbureter and superheater or both.

35 (5) To decrease the fuel used per 1000 cubic feet of gas made.

(6) To increase the volume of gas produced per given time in a given size water 40 gas set.

(7) To prevent excessive clinker formation.

(8) To maintain a high temperature on a greater per cent. of the fuel in the generator.

45 (9) To prevent the caking and arching of the fuel in generator which is a troublesome feature in ordinary operation of a water gas set using bituminous fuel.

In obtaining these results I am taking 50 advantage of the peculiar properties of bituminous fuels, and of the present day standards for city gas, which call for lower heating value and lower candle power than ever before.

As far as I am aware this process is

further distinguished from other processes 55 or from a combination of a water gas and a producer gas process, 1st. In that it allows a greater percentage of up runs to be made, due to the better control of the temperature in the generator, thereby permitting the 60 saving of the rich hydro-carbons and illuminants from the volatile matter of the fuel in the top portion of the fuel bed. (These hydrocarbons are cracked to a great extent 65 when forced down through the fire as with down runs). 2nd. The quantity of steam admitted during air blasting is dependent on the temperatures in the carbureter and superheater, and on the volume of smoke produced during blasting. The gas produced during blasting is entirely consumed within the water gas set and is not passed into a gas holder. 3rd. That definite quantities of auxiliary air and steam are used, and said quantities are under operator's absolute control and are changed by him whenever indications call for a change. 4th. As far as I am aware this process differs further from other processes in that one of the uses of the auxiliary steam,—the steam admitted during the air blasting,—is to increase the volume of high temperature fuel in the generator by preventing the fuel on grates from becoming excessively hot, thereby permitting the use of a greater amount 85 of air blast. The following chemical reactions will help to explain the last statement:

(1) $C + O_2 = CO_2$ exothermic reaction.

(2) $2C + O_2 = 2CO$ exothermic reaction.

(3) $CO_2 + C = 2CO$ endothermic reaction.

(4) $H_2O + C = CO + H_2$ endothermic reaction.

The first three reactions or equivalent are taking place during the ordinary air blasting of a water gas generator. The zone of complete combustion, as in reaction #1, is invariably at the bottom of the generator, and the excessively high heats are, in common practice formed or created in this zone. 95 In my process, on admitting auxiliary steam with the air, reaction #4 takes place, and it takes place at the overheated part of the fire, the zone directly above the grates. This cooling action in the overheated part of the fire permits the heating of a larger zone to the most desirable temperature, which is accomplished by using more blast and by turn-

ing off the auxiliary steam before the end of the blast period. It will be seen that as soon as fire is hot enough above the usual hot zone, the turning off of the auxiliary steam permits the fuel directly above grates to become hot very quickly, particularly with the increased amount of air blast as mentioned. Thus an increased volume of incandescent fuel is obtained.

- 10 In manufacturing water gas by the standard method now in use, (by the Lowe process) it has been shown that the following difficulties are encountered when bituminous fuel is used as generator fuel: Heats in the 15 generator can not be maintained high enough to make water gas for more than a brief period without reblasting generator. On attempting to blast the heats up in the generator by an increased amount of blast, 20 so much combustible gas is produced that it can not all be burned in the carbureter or superheater without overheating them, and if it is burned at the stack endangers melting of the stack and causes a waste of fuel. 25 The big per cent. of tarry matter and volatile matter from the coal produces a heavy voluminous smoke which is emitted at the stack, causing a nuisance. The volume of gas produced, using bituminous fuel in generator, is considerably lower than that produced using good coke as fuel and under the same conditions. The fuel used per 1,000 cubic feet of gas made is considerably greater, using bituminous fuel. Clinker is 30 formed to an excessive degree when bituminous fuel is used in generator and blasted to the necessary temperatures for water gas production.

The figure of the drawing represents a 40 common type water gas generator equipped to manufacture gas by my process using bituminous or other high volatile fuel. In the figure, A represents a generator, with grates B, and fire cleaning door C, and ash pit 45 door D. The charging door is shown at H. E, is the main air blast line to the generator with its air control valve at S. F, is the up run steam line with the steam control valve at T. The down run steam line is 50 shown at G, and its steam control valve at U. The off-take to carbureter for gas made during an up run is at I, and the off-take valve is at J. The down run off-take is at K, and L is the off-take valve. M, is 55 the so-called hydrogen pipe which connects down run off-take with the carbureter. The main steam line is represented by N. The air pressure tank for supplying air to the auxiliary air lines is shown at O. P, and 60 R, represent respectively the auxiliary air lines to the top and bottom of generator, with the common air control valve at Q. The auxiliary steam line to the base of generator is shown at V, with the steam con- 65 trol valve W.

To operate this machine according to my process air is first blasted up through fuel bed by opening valve S on air line E. When fuel bed X is heated to a sufficiently high temperature the air is shut off at valve S, 70 and water gas is produced by admitting steam beneath the grates through up run line F, by opening valve T. A little air is admitted simultaneously through auxiliary air line R, during this steam run. During 75 this run the valve L is closed and valve J is open. This steam with the small amount of air forces its way up through the fuel bed and by chemical combination produces gas. The (CO₂) carbon dioxide 80 formed from the combustion of the auxiliary air is reconverted to (CO) carbon monoxide by the incandescent fuel (according to reaction 3 *supra*) and hence the only diluent of the finished gas is the nitrogen 85 of said air. Now this is partly compensated for by the increase in amount of volatile products from the bituminous fuel, and further compensated for since the hotter fire now obtaining reduces the amount of 90 carbon dioxide (CO₂) which is ever present in water gas; forming in greater per cents. as the fuel temperature decreases. Since CO₂ is the most undesirable inert in combustible gas air should not be used with the 95 steam so long as to increase the percentage of this undesirable element. After this steam run (up run) the steam valve T and the auxiliary air valve Q are closed and the fuel is again blasted from beneath grates 100 by opening the valve S in air blast line. A small amount of steam is simultaneously admitted through the auxiliary steam line V by opening valve W. This produces a richer blast gas (shown in reaction #4 105 *supra*) which is completely burned in the carbureter and superheater with the elimination of smoke and tarry matter which would otherwise be in evidence at stack. This auxiliary steam is not necessarily used 110 during the entire blast period, but just until rich gas is being produced from air blast as will be the case when heat in generator is sufficiently high. The gas first produced on blasting is always very lean. Very little 115 auxiliary steam is used, and usually for but a short time unless carbureter and superheater are not sufficiently hot and more rich gas is needed to heat them, in which case sufficient steam is used to accomplish this 120 end. After this air blast when fuel is sufficiently hot, a down run is made by first turning off air at valve S and turning off steam at valve W, and then admitting steam through the fire from above fuel bed by 125 opening valve U on down run steam line. When this down run is being made, valve L in off-take must be open, and valve J must be closed. While this down run steam is on, a small quantity of air is admitted 130

through the upper auxiliary air line P, by opening valve Q. This air keeps the fuel up to the desired heat for a longer period of steam run, thus increasing the capacity of the water gas set. The cycle is now repeated except that a small amount of auxiliary steam is used on every air blast after the first if conditions require it. It is necessary on blasting with air, or making a steam run that valve L be closed and valve J be open. On all down runs valve J is closed and valve L is open.

Air is nearly always supplied to the main air blast line by a fan or blower, and the air pressure procurable from such fans is usually not great enough to use this source of air to replace the high pressure auxiliary air which I prefer to use in my process. There would be danger of explosion if low pressure air were used during steam runs. For example if a little water condensed in the steam line and was blown into the generator as steam was turned on, the high pressure immediately created would force gas back into the low pressure air line and the gas and air mixture might explode and do damage. A meter, governor and pressure gage should be used on this high pressure auxiliary air supply line. I also prefer to use an auxiliary steam line separate from the regular up run steam line for similar safety reasons. The auxiliary steam admitted through valve W in the figure can be regulated by a governor to give any desired quantity or pressure, but coming through a very small line there is never a possibility of a great quantity of steam entering at once or an excessive pressure being developed, and hence there is no danger of back firing in blast line.

The objects of my process are accomplished as follows:

Object 1 is accomplished by admitting a relatively small volume of air with the steam during the runs, causing combustion to take place and thereby preventing the fuel from becoming superficially chilled, and simultaneously lengthening the run period. Further, object 1 is accomplished by the proper use of up and down runs consistent with the new method of blasting (with the occasional use of steam during the blast) and of making the steam run (by the use of air with the steam during the run).

#2 is accomplished by governing the amount of auxiliary steam admitted during the blast. The more steam admitted at this time the more combustible gas is produced to burn in carburetor and superheater as shown in reaction #4 *supra*.

#3 is accomplished on account of the fact that the slightly leaner water gas, which is produced in increased volume, requires more oil per given period of time to carburet it. This heavier duty for the carburetor and superheater requires that more heat be sup-

plied them and thus is it possible to burn more gas in them without the danger of overheating them.

#4 is accomplished along with #3.

#5 is accomplished by not wasting any combustible gas at the stack of superheater, but by burning it as mentioned in #3 on this page.

#6. The auxiliary air admitted during the gas making period prolongs the gas making period and also produces a greater volume of water gas per given time. This, with the additional volume of gas from the carbureting oil, gives an increased capacity to a given sized water gas set. The additional volume of water gas made is not due chiefly to the added volume of gas from the auxiliary air. The gas made in generator per second during steam run in present practice, is decidedly greater the first few seconds that the steam is admitted and then falls off rapidly. Now, the auxiliary air used in my process during the steam run, prevents the temperature from dropping too rapidly and thus increases considerably this maximum gas making period, and also the volume per given time.

#7 is accomplished due to the fact that the auxiliary steam used during the blast keeps the clinker zone cooler.

#8 is accomplished by the increase in amount of blast.

#9 is accomplished, due to better fire conditions obtaining in the generator; to the benefits derived from admitting auxiliary air during the down runs, and to the increased per cent. of high temperature fuel in generator.

The results obtained during the run with my process are vitally affected by the method of blasting, as well as by the direction of the blast and the amount of air per unit time. This is evident since the quality and quantity of the blue gas produced during the run depend on the condition and temperature of the fuel, and on the volume of the fuel that is heated to a gas making temperature. I am able (by the proper use of air with the steam during the run; with the proper proportion of up and down runs, and with the occasional use of some steam during the blast) to obtain absolute control over the condition of the fuel in the generator and am thereby enabled to make the maximum amount of high quality gas per unit of time during the run. By making up blasts only I maintain the zone of complete combustion, (the hot zone) near the bottom of the generator fuel bed. The incoming steam on all up runs (and most of the runs are up runs) strikes the hottest part of the fuel first, and, being instantly heated to a high temperature has a longer time of contact with the fuel at a high temperature than it would where the steam had to travel half way

through the fuel bed before reaching the highest temperature. The zone of complete combustion being at the lower part of the fuel bed in my process causes the blue gas leaving the generator to leave at a lower temperature than the highest temperature in the generator. This is particularly true on all up runs when the hot gases pass through the green fuel at the top of the generator causing distillation of much of the volatile matter from the fuel, which is retained in the blue gas which is thereby enriched. Since less heat is removed from the generator as sensible heat per unit of gas made, it follows that more heat is available for gas making purposes.

That there is definite coaction between the blast and run in my process is further evident on considering the following: I use up blasts only and use many up runs and some down runs, thus preventing too great a concentration of heat in a particular zone. This is a decided advantage over the processes that use a down blast only and follow them with up runs only, since in these processes a zone of intense heat is created near the top of the fuel bed. In such cases the generator top, off-take valve and off-take pipe are constantly in danger, (danger of over heating and melting) due to the excessive temperature created in this hot upper zone; the blue gas leaves the generator at an excessively high temperature thus causing an increase in the generator fuel per thousand feet of gas made; the steam never strikes the hottest part of the fuel bed first. The ash formed during the down blasts (being near the top of the generator) is, to a considerable extent, carried over into the checker chambers on subsequent runs. This ash deposit is a source of considerable trouble.

In my process I make use of the commonly used carbureting method consisting in blowing or spraying oil into heated checker chambers. I recognize that this is not new and therefore do not claim patent on that process as such. However I obtain a marked improvement in carbureting results and use the old method in a new way.

50 That is:

(1) I make a better grade of blue gas

which contains considerable volatile matter of the fuel, thus the oil is cracked in a different atmosphere.

(2) In using air during the run some producer gas is generated which further changes the atmosphere the oil is cracked in.

(3) Since I make more blue gas (including the volatile from the fuel, and the producer gas made) more oil is required per run with a given size set than in other process, so far as I am aware. This, together with the method of blasting allows for a more perfect control over the temperature in the cracking chambers without the customary waste of blast gases at the stack.

(4) The rate of production of blue gas is more uniform in my process, on account of the air admitted during the run and on account of the better temperature conditions obtaining in the generator, hence the oil concentration in the cracking chambers can be maintained more uniform and the cracking more efficiently done.

I claim:

A process for the manufacture of combustible gas by an intermittent method, using bituminous coal or other solid fuel containing volatile combustible matter, consisting in first heating a bed of ignited fuel in a generator by blasting it with air, using an up blast only, from beneath the fuel bed, and using simultaneously with this air blast a relatively small amount of steam also injected from beneath the fuel bed during the fore part of the blast period only, for the prevention of smoke, prolonging said blast, so as to better heat the upper zones in the fuel bed, shutting off said air, as well as the steam used therewith, and making up-and-down runs, a small quantity of air being injected with the steam, during each of said runs, for the purpose of prolonging the period of said runs, and making at least two up runs to every down run for the purpose set forth.

In testimony whereof I affix my signature in the presence of two witnesses.

WM. WALLACE ODELL.
